GARFIELD A. WOOD, OF DETROIT, MICHIGAN.

TRUCK-BODY-DOOR LATCH.

1,223,462.

Specification of Letters Patent. Patented Apr. 24, 1917.

Application filed September 25, 1916. Serial No. 121,911.

To all whom it may concern:

Be it known that I, GARFIELD A. Wood, a citizen of the United States, and residing at Detroit, in the county of Wayne and State 5 of Michigan, have invented a new and Improved Truck-Body-Door Latch, of which the following is a specification.

It is common practice to tilt the bodies of trucks about pivots located near the rear end 10 of the chassis for the purpose of dumping; it is also common practice to provide the rear ends of these bodies with doors which swing about horizontal pivots located near the upper edges thereof. When the front 15 end of the body is elevated and the door released (particularly when the front wheels of the truck stand on a higher surface than the rear wheels), the latter is swung by gravity into a vertical plane and away from 20 the latching means located on the body, consequently, it is necessary for the driver to go to the rear of the truck and swing the door inwardly into engagement with the latching means before the latching can again 25 take place. The object of the present invention is to provide latching means whereby the door may be readily returned to closed position and locked from a point in proximity to the front end of the body, 30 preferably from a point within reach of a driver sitting on the seat; other objects are to provide means whereby the difficulty ordinarily incident to releasing the door (due to the packing of crushed stone or other material in the body against the door) is avoided, and to provide means whereby the door may be retained in partly open position to allow 35 the escape of material, for example, stone which it is desired to distribute in a layer over the roadway. Its nature will be more 40 fully understood from the following description and the drawings, in which Figure 1 is a fragmentary side elevation, parts being broken away, showing a preferred embodiment of the invention. Fig. 2 is a fragmentary section on about the line 2—2 of Fig. 1.

Upon the rear end of each of the side bars 1 of the truck is rigidly secured a bracket 2 having a pivot 3 about which a body 4 may be swung vertically for dumping purposes by means of a suitable hoisting means, designated 5 as a whole; and the body may be provided at its lower side with the longitudinal frame pieces 6 so arranged as to rest, when in lowered position, either on the side

frames 1 or in special chairs (not shown) carried thereby. This general construction is well known.

The details of the body may be widely varied—as shown, it is of a curved or substantially semi-cylindrical transverse cross section and its rear end is provided with an encircling or reinforcing angle iron 8 having an out-turned flange 9 against which the 65 edge of the door seals. The latter is formed of a sheet metal body portion 10 surrounded by a reinforcing strap or bar 11; near its upper edge inwardly projecting hinge straps 12 inclose the pivot bolt 13 which passes through the angle iron 8 and extends across the body from side to side.

Spaced from and secured to the lower portion of the rear end of the body, for example, by means of bolts or rivets 15, is a 75 stirrup 16 which constitutes a guide for the longitudinally extending portion 18 of a latch bar that also passes through a substantially vertical guide slot of suitable length in the flange 9 and includes at its rear end a 80 hook 19 that, when in locking position, overhangs a striker plate or reinforcing bar 20 which extends across and is riveted to the rear face of the door. The front end of the portion 18 of the latch bar merges into the down-turned arm 21 which preferably extends at about right angles thereto and is pivotally connected at 22 to the connecting rod 23. The latter extends to the front end 85 of the body and is there pivotally connected at 24 to an arm 25 which is rigid with a shaft 26 carried in bearings 28 and having an operating arm or hand lever 29, the upper end of which stands out away from the front end of the body to allow it to be easily seized. It will be understood that the shaft 26 extends across to the opposite side of the body and is there connected to latch mechanism the duplicate of that shown—thus one hand lever actuates both latches. The normally straight connecting rods 23 are resilient and have their intermediate portions carried in guides or clips 30 secured to the body.

Operation: The parts normally stand in 105 the positions shown, from which it will be seen that the rods 23 tend to swing the arms 25 and 29 counterclockwise (Fig. 1) and hold the latter snugly against the front end 110 of the body. In a somewhat similar manner, the rear ends of the rods tend to elevate the front ends of the latch bars 18—21,

which, swinging about the stirrup 16, retain the hooks 19 in proper relation to the bar 20. To release the door the handle is swung into the position shown in dashed lines and 5 slides the latch bar 18—21 substantially straight backward until the portion 21 engages the stirrup 16, which allows the door to swing out far enough to let some of the contents escape, thereby greatly reducing 10 the pressure on the door and allowing the hook to be readily detached from the striker, whereupon the thrust in the rod 23 overcomes the tendency of the latter (because of its 15 resiliency) to hold the hook 19 down and positively swings the latch bar clockwise in the stirrup. The door is then free to swing wide open. Assuming that the front end of the body is now lowered, the door of course swings inwardly, but often, because of the 20 configuration of the surface on which the vehicle stands, or warping of the door, fails to reach the end of the body. However, the length of longitudinal movement of the bars 18 through the stirrups is such that at the 25 initial part of the upward swinging movement of the handle 29, the resiliency of the rods 23 causes the bars 18 to swing down upon the bars 20 with the hooks 19 to the rear of the latter. Continued movement of 30 the handle then draws the bar 18—19 directly forward until the door is firmly seated against the flange 9, after which a slightly further movement brings the pivots 24 above the lines joining the pivots 26 and guides 30, in which position the parts are automatically 35 locked by the resiliency of the rods. By properly manipulating the lever 25—29, the door may be allowed to swing partly open, the hook still being maintained in holding 40 relation to the striker, thus providing a restricted end gate particularly useful in distributing stone or the like in a layer over the roadway.

It will be seen that the handle 29 may be 45 grasped by a driver sitting on the seat 31.

The details of the device may obviously be changed without departing from the spirit of the invention; for example, while particularly suitable in connection with 50 swinging bodies, the latch mechanism may be applied to a vehicle in which the body is fixed to the frame, that is, non-pivoted; I do not, therefore, wish to be limited except as indicated by the subjoined claims.

55 I claim:—

1. In combination with a vehicle body arranged to be swung about a horizontal axis near the rear end of the vehicle and having at its rear end a door arranged to swing 60 about a horizontal axis located near the upper edge of the body, means for latching the door located below the last mentioned axis, said means including a latch bar having a sliding movement longitudinally of 65 said vehicle and also having a swinging

movement, and means associated with said latch bar for sliding the latter rearwardly a predetermined distance from the position it occupies when the door is entirely closed and thereafter positively swinging said latch 70 bar out of the path of the door, whereby the latch bar is caused to positively release the door after the latter has swung to partly open position.

2. In combination with a vehicle body arranged to be swung about a horizontal axis near the rear end of the vehicle and having at its rear end a door arranged to swing about a horizontal axis located near the upper edge of the body, means for latching 80 the door located below the last mentioned axis, said means including a striker on the door, a guide on the body, a latch bar co-operating with the striker and having a sliding movement in said guide longitudinally of said vehicle and also having a swinging movement in said guide, and an operating rod pivotally connected to the latch bar whereby the latch bar, in latching the door, is first swung into engagement 90 with the striker and afterward drawn forward by a sliding movement until the door is closed, and a hand lever also pivoted to the operating rod, said hand lever being movable to a position in which the door is closed, said body including means for limiting the movement of said hand lever in the direction stated, and said rod being arranged to automatically retain the lever in engagement with the movement limiting 95 means.

3. In combination with a vehicle body arranged to be swung about a horizontal axis and having a door arranged to be swung about an axis substantially parallel to the first mentioned axis, means for latching the door located below the last mentioned axis, said means including a striker on the door, a latch bar co-operating with the striker and having a sliding movement and also having a swinging movement, an operating rod pivotally connected to the latch bar, and means associated with said latch bar and co-operating with said operating rod to positively swing the latch bar out of the path of the 105 striker after the latch bar has been slid rearwardly a predetermined distance.

4. In combination with a vehicle body arranged to be swung about a horizontal axis and having a door arranged to be swung about an axis substantially parallel to the first mentioned axis, means for latching the door located below the last mentioned axis, said means including a striker on the door, a guide on the body, a latch bar co-operating with the striker and having a sliding movement in said guide and also having a swinging movement in said guide, an operating rod pivotally connected to the latch bar whereby the latch bar, in latching the door, 115

120

125

130

is first swung into engagement with the striker and afterward drawn by a sliding movement until the door is closed, and a hand lever also pivoted to the operating rod, 5 said hand lever being movable to a position in which the door is closed, said body including means for limiting the movement of said hand lever in the direction stated, and said rod being arranged to automatically 10 retain the lever in engagement with the movement limiting means.

5. In combination with a vehicle body arranged to be swung about a horizontal axis and having a door arranged to be swung 15 about an axis substantially parallel to the first mentioned axis, means for latching the door located below the last mentioned axis, said means including a striker on the door, a guide on the body, a latch bar coöperating 20 with the striker and having a sliding movement in said guide and also having a swinging movement in said guide, an operating rod supported by the body and pivotally connected to the latch bar, a pivotally 25 mounted hand lever supported by the body and pivoted to the operating rod, and a guide for an intermediate portion of the rod, said guide being out of alinement with the line joining the point at which the rod is 30 connected to the latch bar to the point at which it is connected to the lever whereby the latch bar, in latching the door, is first swung into engagement with the striker and afterward drawn by a sliding movement until 35 the door is closed.

6. In combination with a vehicle body arranged to be swung about a horizontal axis and having a door arranged to swing about an axis substantially parallel to the first 40 mentioned axis, means for latching the door located below the last mentioned axis, said means including a striker on the door, a guide on the body, a latch bar slideable and swingable in said guide, said latch bar including a hook for coöperation with the 45 striker, a body portion passing through the guide and an arm extending at an angle to the body portion, an operating rod supported on the body and pivotally connected 50 to said arm, means for manually moving said operating rod, said rod being arranged to normally urge the body portion of the latch bar into engagement with the striker, and serving to first slide the latch bar in the 55 guide until the arm contacts therewith and thereafter to swing the latch bar away from the striker to release the latter.

7. In combination with a vehicle body arranged to be swung about a horizontal axis 60 and having a door arranged to swing about an axis substantially parallel to the first mentioned axis, means for latching the door located below the last mentioned axis, said means including a striker on the door, a 65 guide on the body, a latch bar slideable and

swingable in said guide, said latch bar including a hook for coöperation with the striker, a body portion passing through the guide and an arm extending at an angle to the body portion, an operating rod pivotally 70 connected to said arm, the line joining the ends of said rod being appreciably out of alinement with said guide, said rod tending, when the arm of the latch bar is in engagement with the guide, to swing the latch bar 75 away from the striker and tending in all other positions of the latch bar to maintain the latter in close engagement with the striker, whereby the striker may first be seized and then drawn toward the body to 80 close the door.

8. In combination, a vehicle body arranged to be swung about a horizontal axis near the rear end of the vehicle, said body having a reinforcing bar extending peripherally about its rear end, said bar having an out-standing slotted flange, a connecting member passing across the body from side to side near the upper rear edge, a door pivotally hung on said connecting member, said 90 door being adapted to seat against the slotted flange, a striker on said door, a guide carried by the body adjacent the slot in the flange, a latch bar having sliding and swinging movements in said guide and slot and 95 including an arm at an angle to the remainder thereof, a forwardly extending operating rod pivoted to the arm, manually controlled means, operable in all positions of the body, for moving the rod longitudinally of the body, said rod, when in rear-most position, causing the arm to contact with the guide and swinging the remainder of the bar away from the striker, and when in other positions tending to swing the bar 100 about the guide and into contact with the striker whereupon the bar may be drawn forwardly by said rod substantially longitudinally of the vehicle.

9. In combination with a vehicle body arranged to be swung about a horizontal axis and having a door arranged to swing about an axis substantially parallel to the first mentioned axis, means for latching the door located below the last mentioned axis, said 110 means including a striker on the door, a hooked latch bar mounted to swing on the body into engagement with the striker, a bell crank pivotally mounted on the body, a portion of the bell crank being adapted to 115 engage a portion of the body, a connecting rod pivotally connected to another portion of the bell crank and to an arm on the latch bar, and a guide for an intermediate portion of the rod, the line between said guide 120 and the pivot whereby the rod is joined to the bell crank being so positioned with reference to the pivot for the bell crank as to automatically hold the bell crank tightly in engagement with the body when the latch 125 130

bar is in engagement with the striker and the door is closed.

10. In combination with a vehicle body having a door arranged to be swung about a horizontal axis, means for latching the door located at a level different from that of the axis, said means including a striker on the door, a latch bar coöperating with the striker and having a sliding movement and also 10 having a swinging movement, an operating rod pivotally connected to the latch bar, and means associated with said latch bar and coöperating with said operating rod to positively swing the latch bar out of the path of 15 the striker after the latch bar has been slid rearwardly a predetermined distance.

11. In combination with a vehicle body having at its rear end a door arranged to swing about a horizontal axis located near 20 the upper edge of the body, means for latching the door located below the last mentioned axis, said means including a striker on the door, a guide on the body, a latch bar coöperating with the striker and having a 25 sliding movement in said guide longitudinally of said vehicle and also having a swinging movement in said guide, and an operating rod pivotally connected to the latch bar whereby the latch bar, in latching the door, 30 is first swung into engagement with the striker and afterward drawn forward by a sliding movement until the door is closed, and a pivotally mounted hand lever also pivoted to the operating rod, the center 35 about which the hand lever swings being located between the ends of the operating rod, and said operating rod being arranged to be swung by said hand lever across the line joining the rear end of said rod to said center 40 in closing the door for automatically retaining the hand lever in position.

12. In combination with a vehicle body having a door arranged to be swung about a horizontal axis, means for latching the door 45 coöperating with the latter at a different level from that of the axis, said means including a striker on the door, a guide on the body, a latch bar coöperating with the striker and having a sliding movement in 50 said guide and also having a swinging movement in said guide, an operating rod pivotally connected to the latch bar, a pivotally mounted lever pivoted to the operating rod, and a guide for an intermediate portion of 55 the rod, said guide being out of alinement with the line joining the point at which the rod is connected to the latch bar to the point at which it is connected to the lever whereby the latch bar, in latching the door, is first 60 swung into engagement with the striker and afterward drawn by a sliding movement until the door is closed.

13. In combination with a vehicle body having a door at its rear end arranged to be 65 swung about a horizontal axis located near

the upper edge of the door, means for latching the door coöperating with the latter at a point below the axis, said means including a striker on the door, a guide on the body, a latch bar slidable and swingable in said 70 guide, said latch bar including a hook for coöperation with the striker, a body portion passing through the guide and an arm extending at an angle to the body portion, an operating rod pivotally connected to said 75 arm, said rod being arranged to normally urge the body portion of the latch bar into engagement with the striker, and serving to first slide the latch bar in the guide until the arm contacts therewith and thereafter to 80 swing the latch bar away from the striker to release the latter whereby said door may be made to constitute a restricted end gate.

14. In combination with a vehicle body having a door at its rear end arranged to be 85 swung about a horizontal axis located near the upper edge of the door, means for latching the door coöperating with the latter at a point below the axis, said means including a striker on the door, a guide on the body, a 90 latch bar slidable and swingable in said guide, said latch bar including a hook for coöperation with the striker, a body portion passing through the guide and an arm extending at an angle to the body portion, and means whereby said latch bar is limited to a 95 substantially rectilinear path and is held in engagement with the striker during the first part of its movement and is subsequently swung in the guide to release the striker. 100

15. In combination, a vehicle body having a reinforcing bar extending peripherally about its rear end, said bar having an outstanding slotted flange, a connecting member passing across the body from side to side 105 near the upper rear edge, a door pivotally hung on said connecting member, said door being adapted to seat against the slotted flange, a striker on said door, a guide carried by the body adjacent the slot in the flange, a latch bar having sliding and swinging movements in said guide and slot and including an arm at an angle to the remainder thereof, a forwardly extending operating rod pivoted to the arm, said rod, when in rearmost 110 position, causing the arm to contact with the guide and swinging the remainder of the bar away from the striker, and when in other positions tending to swing the bar about the guide and into contact with the striker 115 whereupon the bar may be drawn forwardly by said rod substantially longitudinally of the vehicle. 120

16. In combination, a vehicle body having a reinforcing bar extending peripherally 125 about its rear end, said bar having an outstanding slotted flange, a connecting member passing across the body from side to side near the upper rear edge, a door pivotally hung on said connecting member, said door 130

being adapted to seat against the slotted flange, a striker on said door, a guide carried by the body adjacent the slot in the flange, a latch bar having sliding and swinging movements in said guide and slot, means coöoperating with said bar for causing a portion thereof to contact with the guide when in rearmost position and thereafter swinging

the bar in said guide and away from the striker, said means, when in other positions, tending to swing the bar about the guide and into contact with the striker whereupon the bar may be drawn forwardly by said rod substantially longitudinally of the vehicle. 10
